UNITED STATES PATENT OFFICE.

MAX ROCKSTROH, OF KLEIN-SEDLITZ, NEAR PIRNA, GERMANY.

ROTARY TRANSMISSION-DYNAMOMETER WITH RECORDING APPARATUS.

1,183,675.

Specification of Letters Patent.

Patented May 16, 1916.

Application filed March 24, 1914. Serial No. 826,937.

To all whom it may concern:

Be it known that I, MAX ROCKSTROH, manufacturer, a subject of the King of Saxony, residing at Klein-Sedlitz, near Pirna, Saxony, Germany, have invented certain new and useful Improvements in Rotary Transmission-Dynamometers with Recording Apparatus, of which the following is a specification.

10 This invention relates to rotary transmission dynamometers, with recording apparatus, of the type wherein the torque acts, through a fluid, on a piston or plunger rotating with the shaft.

15 The invention consists in arranging that the movement of the said rotating piston or plunger is transmitted, in the form of an axial thrust, to a piston or plunger, preferably of larger diameter, which does not 20 rotate and transmits the thrust to a stationary recording apparatus at a distance. The use of a stationary plunger of larger diameter affords considerable advantages in regard to tightness and transmission to the 25 recorder.

The invention is illustrated in the accompanying drawings, in which—

Figure 1 is a cross section of the shaft with part of the mechanism. Fig. 2 is a 30 longitudinal section thereof, and Fig. 3 shows the recording apparatus, which is of a known type.

In the drawing *a* designates a shaft, which has an axial bore *a'* and to which is fixed 35 a collar or holder *b* carrying a cylinder *c* with a piston *c'* therein. The interior of the cylinder *c* communicates by means of pipe *c''* and radial duct *c'''* with the axial bore *a'* adapted to receive a pressure fluid. A 40 pulley *d* loose on the shaft *a* carries a driver member *e* arranged to abut against the outer face of the piston *c'*, so that rotation of the pulley in the direction indicated by the arrow in Fig. 1 drives the piston *c'* into the cylinder *c* and imparts rotation to the shaft. An enlarged part of the bore *a'* contains a 45 piston or plunger *g*, which projects out of the shaft into a housing *h* fixed to the bearing *f*. A cylindrical extension *h'* of the 50 housing *h* contains a plunger *i* facing the plunger *g*, the plunger *i* being of larger diameter than the plunger *g*. It will be seen that the piston *c'*, acting through the fluid

in the cylinder and the bore *a'*, drives the plunger *g* against the plunger *i*, and forces 55 the latter toward the outer end of the cylinder *h'*, which is closed except where joined to a pipe *k*. The plunger *i* expels through the pipe *k* a pressure fluid which acts on a plunger *l* forming part of the recording apparatus *m*. The plunger *l* is connected to one end of a double armed lever *o*, the other end of which is attached to a spring *p*. The lever actuates a style-holder *n*, which works in front of a chart rotated, as indicated by 60 the arrow in Fig. 3, by the clockwork of the recording apparatus.

Having now particularly described and ascertained the nature of my said invention and in what manner the same is to be performed, I declare that what I claim is:—

1. In a device of the character described, the combination of a fly-wheel loosely mounted upon the engine shaft provided with an axial bore, a plunger within said bore 75 adapted to rotate with said shaft, a housing secured to said shaft, a non-rotating plunger of a larger diameter than said first named plunger within said housing facing the same, and means connected to said second plunger for operating a recording apparatus by a liquid pressure means, said second named plunger being adapted to receive the thrust of said first named plunger in axial direction, substantially as described 80 and for the purpose set forth.

2. In a device of the character described, the combination of a fly-wheel loosely mounted upon the engine shaft and provided with an axial bore, a plunger within said bore 90 rotating with said shaft, a housing secured to said shaft, a non-rotating plunger within said housing facing said first named plunger and adapted to receive the thrust of the same in axial direction, and means connected 95 to said plunger for operating a recording apparatus by a liquid pressure means, substantially as described and for the purpose set forth.

In testimony whereof I have hereunto set 100 my hand in presence of two subscribing witnesses.

MAX ROCKSTROH.
